UNITED STATES PATENT OFFICE.

CHARLES E. McMANUS, OF NEW YORK, N. Y.

BOTTLE CLOSURE AND PROCESS OF MAKING SAME.

Application filed July 6, 1922. Serial No. 573,179.

My invention relates to a bottle closure of the type generally known as a crown cap, and more particularly to a closure of this kind in which the ordinary cork cushion is dispensed with; and to the process of making such closures.

Heretofore it has been the common practice to make bottle closures of the type known as crown caps, of a metallic shell having suitably bonded thereto, a sealing or cushion disk of approximately one-sixteenth of an inch in thickness and formed of natural or, so called, composition cork. Such closures have been in extensive use for many years. In the use of such closures, the sealing is effected by the distortion of the sealing or cushion disk as a result of fairly heavy pressure applied thereto through the metallic shell while the disk is in engagement with the mouth of a bottle. With closures of this character, there is always apt to be a certain percentage of imperfect seals resulting in what is known in the trade as "leakers", which is due in some instances to imperfections in the cork and in other instances to imperfections in the pouring lip of the bottle.

The cushion or sealing disk employed in such caps is sometimes acted upon by the contents of a bottle, some liquids having a tendency to blacken natural or composition cork and to attack the binder in the latter. To meet this condition, facing disks, or a paraffin or other wax surface, are sometimes applied to the exposed surface of the cushion or sealing disk in order to protect this surface from the contents of a bottle.

With the above conditions in mind, I have provided a closure employing the form of metal shell usually used in crown caps, and a special form of cushion, which will possess sufficient resiliency to form an effective seal about the top of the mouth of a bottle and about the outer edge thereof, which sealing disk is of relatively less thickness than the ordinary cork or composition cork cushion or sealing disk, thus permitting a shell of less depth to be used without interfering with the locking action of the fluted edge beneath the bead of the neck of the bottle. This cushioning or sealing member

is formed of soft vulcanized rubber bonded to the inner top of the shell and cupped so as to provide a flange extending about the cylindrical top portion of the shell, so as to provide flexible areas which may be engaged by the top of the bottle and by the outside of the neck of the bottle so as to provide a double seal as a result of the compression of the rubber adjacent both of said areas, as the closure is applied to a bottle by the usual capping machine.

In order to avoid any possibility of the contents of a bottle contacting with the rubber of the sealing medium, I provide the closure with a non-absorptive facing disk which is bonded to the cushioning member in a position to be interposed between same and the top of a bottle. While this facing disk is ordinarily of a diameter to engage the top of a bottle, it does not extend about the sides of the cylindrical top portion of the shell, thus affording a rubber to glass seal about the edge of the bottle mouth notwithstanding that there may be a paper to glass seal at the top thereof. In producing bottle closures embodying my invention, the difference between the diameters of the rubber portion of the cushion or seal and of the facing disk therefor, necessitates the independent application of these portions of the cushion or seal to the metal shell, the object of the process of my invention being to assemble these parts in a shell by a continuing operation, so as to ensure the economical production of the closure and avoid a re-handling thereof after the rubber has been applied to the shell in order to include the facing disk in the completed product.

The invention consists primarily of a bottle closure consisting of a shell having a fluted edge, a cylindrical top portion and a top adapted to be secured to the neck of a bottle and a cushion within said shell consisting of a skirted resilient member covering the inner top of the shell and having the skirt thereof extend parallel with and in engagement with said cylindrical top portion extending about the edges thereof adjacent said top; and in other novel characteristics, and in the process of making said shell, all as hereinafter set forth and

described, and more particularly pointed out in the claims hereto appended.

Referring to the drawings,

Fig. 1 is a cross section of a closure embodying my invention;

Fig. 2 is a plan view of the inside thereof; and

Fig. 3 is a diagrammatic showing of the process or method of making the closure.

Like letters refer to like parts throughout the several views.

In the embodiment of my invention shown in the drawings, I employ a metallic shell having the ordinary fluted edge *a*, cylindrical top portion *b* and top *c*. Within and bonded to the top *c* of the shell and extending about the cylindrical top portion *b* adjacent thereto, is a cupped sealing member of soft vulcanized rubber or other similar resilient material, having a top *d* and skirt *d'*, the depth of the skirt *d'* being sufficient to engage the outside of the bead about the mouth of a bottle so that when applying the closure to the bottle, the top *d* of said member will be compressed throughout the area of engagement of the top of the bottle therewith and the skirt *d'* will be compressed throughout the area of engagement of the skirt *d'* with the outside of the bead, thus affording a double seal which will effectively prevent the escape of liquid or gases from within the bottle.

Since the material of the member *d* and the skirt *d'* thereof is both impregnable to gas and liquid and immune to the action of many chemicals, the kind of binder, adhesive or glue used in bonding said member to the top of the shell and about the cylindrical portion thereof, is immaterial, although I preferably use the ordinary binders, adhesives or glues commonly used in this art; that is either copal gum adhesive, or adhesives containing albumen or casein, the so-called solvents of which are removed as a result of the application of heat thereto, and the body of which is made tacky as a result of the expulsion of moisture therefrom, and the application of heat thereto, while the members being united, are subjected to pressure.

To avoid any possibility of the characteristic taste of rubber being imparted to the contents of a bottle, I cover this area of the top *d*, which is substantially coincident with that of the top *c*, with a facing disk *e* of a fibrous material such as paper impregnated with a suitable oil or wax which will make it substantially non-absorbent, said sealing disk *e* being bonded or cemented to the member *d* preferably by means of the same binder, adhesive or glue as is used when bonding said member *d* to the shell. This construction is desirable, particularly as it presents a neat appearance to the finished article and does not materially in-

crease the cost of production of the closure, since the entire device may be assembled with one handling thereof when following the process of my invention.

While I preferably use a fluted skirt *a* upon the shell as a means for securing it to the neck of a bottle, it is understood that the skirt may be so formed as to adapt the closure to different types of capping machines, the fluted skirt being old and well known in the art and forming no part of my present invention. While I have referred to a metal shell, it is apparent that the material of the shell is immaterial to my present invention.

The use of a non-absorbent disk *e* is for the purpose of preventing the liquid contents of a bottle from attacking the binder, adhesive or glue, bonding said disk to the top *d* of the sealing member. The inside of the shell is preferably coated with a suitable lacquer, baked after being applied thereto, as I find the use of a lacquer coated shell secures a more effective bond between the cushion or sealing member than can be procured by a plain tin shell wherein grease or oil spots are apt to occur, and interfere with the proper bonding of the cushioning or sealing member to the shell.

A shell embodying my invention is produced by the process substantially as follows:

The shell is first coated upon the inside thereof upon the top *c* and the cylindrical portion *b* adjacent thereto, with a suitable binder, adhesive or glue. A disk of soft vulcanized rubber and of a diameter relatively greater than the top *c*, is then fed in relation to said shell and forced thereinto by a suitable plunger *f* so as to simultaneously cut the material of the member *d* to form the skirt *d'*, and at the same time bring the entire inner surface thereof into intimate engagement with the adhesive coated interior of the shell. The plunger *f* is then withdrawn and a suitable adhesive is applied to the exposed surface of the member *d* but not of the flange *d'* thereof, and thereafter the disk *e* is deposited within the shell upon the adhesive coated surface of the member *d*. When the parts are in this relation, pressure is applied to the facing disk *e* and therethrough and through the top *d* and the top *c* by a plunger *g* and against a suitable backing *h* heated in any desired manner as by the gas burner *i*. The closure is thus placed under a continuing pressure and subjected to heat for a sufficient interval to dry the moisture contained in the binder, adhesive or glue, and reduce said binder, adhesive or glue to a tacky condition, the continuing pressure ensuring the desired intimate relation of the surfaces to be bonded together as in ordinary gluing. After the shell and its contents have been subjected to heat and

pressure for the desired interval, approximately ten to twenty seconds, the pressure from the cap is relieved, and the cap is removed from adjacent the heating medium so as to subject it to a reduced temperature which will effect the setting of the binder, adhesive or glue. This setting occurs very rapidly even under normal temperatures.

When a closure embodying my invention is applied by the usual capping machine, to the mouth of a bottle, the top *d* of the sealing or cushioning member adjacent the top *c* of the shell, will be compressed or distorted as a result of the pressure applied to the shell, and at the same time the skirt *d'* of the cushion or sealing member will be compressed by engagement with the outer edge of the bead at the mouth of the bottle, thus securing a double seal through independent areas of the resilient member.

The facing disk *e* will yield sufficiently and be subject to sufficient distortion under such pressure to avoid the formation of any material channels between same and the top *c* of the mouth of a bottle, notwithstanding that the total aggregate thickness of the top *d* and of the member *e* will be but approximately one thirty-secondth of an inch or less than one-half the thickness of the ordinary cork cushion disk.

The disk *e* will effectively prevent any contact of liquid within a bottle with the rubber of the member *d*—*d'*.

A bottle closure embodying my invention may be effectively used with uncharged as well as charged beverages, and affords a tight liquid and gas impervious joint between the closure and the bottle.

Such a closure may be economically produced, since the material forming the member *d*—*d'* and the facing disk *e*, may be obtained upon the open market at a cost less than that of the natural cork disks, or producing composition cork disks, and the method of producing the closure does not involve any rehandling thereof.

Closures embodying my invention may be produced more economically than the old type of caps having a cork or composition cork seal, and will under all circumstances have greater uniformity in their sealing action than the old type of caps above referred to, as little difficulty is experienced in bonding the member *d*—*d'* to the shell and the member *e* to the top *d*, and voids such as are a frequent occurrence with natural or composition cork, do not occur in soft vulcanized rubber or the fibrous material of the facing disk *e*.

It is not my intention to limit the invention to the precise details of construction shown in the accompanying drawings, it being apparent that such may be varied without departing from the spirit and scope of the invention.

Having described the invention, what I claim as new and desire to have protected by Letters Patents, is:—

1. A bottle closure consisting of a shell having a fluted skirt, a cylindrical top portion and a top adapted to be secured to the neck of a bottle and a cushion within said shell consisting of a skirted resilient member covering the inner top of the shell and having the skirt thereof extend parallel with and in engagement with said cylindrical top portion extending about the edges thereof adjacent said top.

2. A bottle closure consisting of a shell having a fluted skirt, a cylindrical top portion and a top adapted to be secured to the neck of a bottle and a cushion within said shell consisting of a skirted resilient member covering the inner top of the shell and having the skirt thereof extend parallel with and in engagement with said cylindrical top portion extending about the edges thereof adjacent said top, and a facing disk of non-absorbent material cemented to said skirted resilient member so as to be positioned between said member and the contents of a bottle.

3. A bottle closure consisting of a shell having a fluted skirt, a cylindrical top portion and a top adapted to be secured to the neck of a bottle and a cushion within said shell consisting of a skirted resilient member covering the inner top of the shell and having the skirt thereof extend parallel with and in engagement with said cylindrical top portion extending about the edges thereof adjacent said top, and a facing disk of non-absorbent material, the diameter of which is substantially the same as the top of said shell, cemented to said skirted resilient member so as to be positioned between said member and the contents of a bottle.

4. A bottle closure consisting of a shell having a fluted skirt, a cylindrical top portion and a top adapted to be secured to the neck of a bottle and a cushion within said shell consisting of a skirted resilient member covering the inner top of the shell and having the skirt thereof extend parallel with and in engagement with said cylindrical top portion extending about the edges thereof adjacent said top, and a facing disk of fibrous material impregnated with a moisture resisting substance, cemented to said skirted resilient member so as to be positioned between said member and the contents of a bottle.

5. A bottle closure consisting of a shell having a fluted skirt, a cylindrical top portion and a top adapted to be secured to the neck of a bottle and a cushion within said shell and bonded thereto consisting of a skirted rubber member covering the inner top of the shell and having the skirt thereof extend parallel with and in engagement with said cylindrical top portion extending about

the edges thereof adjacent said top, and a facing of fibrous material of substantially the same diameter as the top of said shell bonded to said rubber member so as to be positioned between said member and the contents of a bottle.

6. The herein described process of making a bottle closure consisting of delivering a disk of resilient material to an adhesive 10 coated shell having a fluted skirt, a cylindrical top portion and a top, and simultaneously forming said disk into cup shape to form a skirt about and in engaging relation with the cylindrical top portion of said shell, 15 applying adhesive to the bottom of said cup shaped resilient material, delivering a fibrous

disk within said cup shaped resilient material upon the adhesive coated surface thereof with the periphery thereof in substantial engagement with the skirt of said disk, applying pressure towards the top of said shell to said fibrous disk and said resilient material, simultaneously subjecting said shell and its contents to heat while such pressure is being applied thereto, and thereafter exposing the cap to a reduced temperature to set the adhesive. 20 25

In witness whereof I have hereunto affixed my signature this 23rd day of June 1922.

CHARLES E. McMANUS.
